THERMIONIC DEVICE

Edward A. Rockwell, Chicago, Ill., assignor to
Patent Engineering Corporation, a corporation
of Delaware

Application October 13, 1931. Serial No. 568,552

7 Claims. (Cl. 250—27.5)

This invention relates to improvements in thermionic devices and has for an object the provision of flexible means between the reentrant stem of such a device and the element assembly thereof.

Another object of the invention is the provision in a thermionic device of filament supports adapted to support the filaments in definite and fixed space relation to the envelope of the device.

10 A further object of the invention is the provision of an element assembly or structure in a thermionic device flexibly mounted before insertion in the envelope and adapted to remain in fixed relation to the envelope after being inserted therein regardless of any misalignment in the mounting.

Still another object of the invention is the provision in a thermionic device of a flexible support for the element assembly thereof, adapted 20 to act as an electrical conductor for one of the elements of the device.

Other objects and advantages will be apparent to those skilled in the art upon perusal of this specification and the appended claims.

25 Referring to the drawing:

Figure 1 is a view, partly broken away, of a thermionic device constituting one embodiment of the invention;

Figure 2 is a sectional view along the line 2—2
30 of Figure 1;

Figure 3 is a view of a portion of a thermionic device showing one modification of the invention; and

Figures 4 and 5 show other modifications of
35 the invention.

The element assembly in the preferred form shown herein consists of a central metallic member 10 having an anode 11 supported thereon in any suitable manner, such as by a metallic cross piece 12 which may be welded to the anode 11 and to the metallic member 10. The part 12 may have one end extended downwardly to support a "getter" 13. A filamentary cathode 14 surrounds the anode or plate 11. This cathode 40 is in the form of a zigzag filament which may be supported by any suitable means such a plurality of hooks 15 carried by a glass bead 16 at the upper end of the metallic member 10, and a second set of hooks 17 carried by a glass bead 18 secured to the member 10 at a point below the bead 16. Viewed from above the upper hooks are 45 preferably not in line with the lower hooks.

These hooks are of such length that their extremities fit the interior of the glass envelope 50 19 when the element structure is placed therein.

The member 10 has a twist 24 therein between the lower bead 18 and the "press" 20 of the stem 21, and this member 10 is adapted to form a conductor between the anode 11 and one of the prongs in the base of the device which will be 60 presently described.

Sealed into the "press" 20 of the stem 21 along with the member 10 are the conductors 22 and 23 to which the filament or cathode 14 is connected.

65 The member 10 supporting the anode 11 and the beads 16 and 18 thereon supporting the upper and lower hooks 15 and 17 carrying the filament 14, comprises an "element structure" which is flexibly supported on the stem by the member 70 10 having the twist 24 therein. This twist allows the element structure to move angularly with respect to the center axis of the stem in any direction, so that when the "element structure" is assembled into the glass envelope 19, the hooks 75 15 and 17 fit the interior thereof and hold the element structure definitely in fixed relation thereto, and when the stem 21 is sealed into the envelope 19, any variations or inaccuracies in this process will not affect this fixed relation. 80

This relation between the elements and the envelope is important in thermionic devices such as described in the co-pending application, Serial No. 566,008, filed September 30, 1931, by Earl L. Koch in connection with which an outside grid 85 is used.

This construction also has a distinct advantage in that thermionic devices so constructed will stand very rough handling, it being impossible to dislocate the element assembly without breaking 90 the glass envelope.

It is obvious that more elements than those above named could comprise the "element structure" without departing from the spirit of the invention, and in four and five element tubes 95 where the element structure becomes top heavy the herein described method of locating the assembly within the envelope eliminates the breakage now prevalent with these types of tubes.

After the stem 21 is sealed into the envelope 19 and the device is evacuated and sealed off, a base 24 may be secured thereto and the conductors are connected to the prongs thereof, two of which 100 are shown at 25 and 26.

105 In the modification shown in Figure 3, the central member 10a is shown as a straight metallic rod, preferably of flexible or springy material, and while shown as one piece, it may consist of metals of different character welded together to 110

support the element structure flexibly on the stem 21.

In the modification shown in Figure 4, the central member 10b has a portion of its length between the lower bead 18 and the press 21 of the stem 20 formed into a helix 27.

In the modification shown in Figure 5, the central member 10c has a portion of its length between the lower bead 18 and the press 21 of the stem 20 formed into an S shaped loop 28.

Many other modifications may be made by those skilled in the art without departing from the invention.

While no grid is shown in the drawing, the embodiment of the device as shown in Figure 1 contemplates the use of a grid fitting the outside of the glass envelope. This grid may be in the form of a sleeve or it may be in the form of a cap and it may be made of any suitable material such as is described in the co-pending application above referred to, and with the grid omitted the device may be used as a diode or as a rectifier.

What is claimed is:

1. In a thermionic device, an element structure including an anode and cathode, a stem having said structure flexibly supported thereon, and an enclosing envelope adapted to be assembled therewith, the interior walls of the envelope contacting with and laterally positioning said structure therein.

2. In a thermionic device, an element structure including an anode and cathode said cathode being supported on said structure by radial members, and a sealed envelope enclosing said structure and having its inner wall contacting with said members thereby holding said filament in definite space relation to said wall.

3. In a thermionic device, an element structure including a filament supported by two groups of radial members spaced apart, a sealed envelope

enclosing said structure and having its inner wall contacting with some of said members thereby supporting said structure and holding said filament in definite space relation to said wall, a reentrant stem in said envelope, and a flexible member between said element structure and said stem.

4. In a thermionic device, a sealed glass envelope having a reentrant stem, and an element structure including radial members within the envelope flexibly supported by said stem and held in fixed relation to the inner wall of the envelope by said members.

5. In a thermionic device, an element structure including a plate and a filament, a plurality of members above and below said plate extending beyond the outer diameter thereof and adapted to support the filament thereabout, and a glass envelope surrounding said structure and having its inner wall contacting with said members thereby retaining the elements of said structure in fixed relation thereto.

6. In a thermionic device, an enclosing envelope having a reentrant stem, a flexible member passing through said stem in sealed relation thereto, an anode secured to said member, supports secured to said member above and below said anode, and a cathode on said supports surrounding the anode and held in fixed space relation to the wall of said envelope thereby.

7. In a thermionic device, an enclosing envelope having a reentrant stem, a flexible member passing through said stem in sealed relation thereto, an anode secured to said member, filament supports secured to said member and having radial arms with their outer ends contacting with said envelope, and a filament supported by said arms and disposed between the anode and the inside wall of said envelope.
